UNITED STATES PATENT OFFICE.

WILLIAM P. KRAMER, OF SAGINAW, MICHIGAN.

AUTOMOBILE WORKSTAND.

Application filed November 3, 1921. Serial No. 512,434.

To all whom it may concern:

Be it known that I, WILLIAM P. KRAMER, a citizen of the United States, and a resident of Saginaw, in the county of Saginaw and State of Michigan, have invented a new and Improved Automobile Workstand, of which the following is a full, clear, and exact description.

This invention relates to improvements in automobile work stands, an object of the invention being to provide a stand of this character in which a car may be placed and the stand may be moved to turn the car about into any convenient position for the purpose of repairs.

A further object is to provide a simple and practical operating means for turning the stand, and to provide a stand which will be strong, durable and efficient in use, and comparatively inexpensive to manufacture.

With these and other objects in view, the invention consists in certain novel features of construction and combinations and arrangements of parts as will be more fully hereinafter described and pointed out in the claims.

In the accompanying drawings:

Figure 1 is a view in side elevation of my improved supporting stand showing a car in position therein;

Figure 2 is an enlarged end view of Figure 1.

Figure 3 is a view similar to Figure 2 showing the position of the car after the stand has been operated;

Figure 4 is an enlarged view in transverse section on the line 4—4 of Figure 2;

Figure 5 is a view in transverse section on the line 5—5 of Figure 2;

Figure 6 is a similar view on the line 6—6 of Figure 2;

Figure 7 is a fragmentary detail view of the ratchet and pawl mechanism with parts broken away for clearness;

Figure 8 is another view of the pawl;

Figure 9 is a view in section on the line 9—9 of Figure 1; and

Figure 10 is a side view of Figure 9.

Referring in detail to the drawings, I have used the reference numerals 1, 1 to denote a pair of coacting semi-circular angle plates which cooperate to form a track. These angle plates or bars include parallel sides 2 connected by substantially

U-shaped clips 3 and spaced apart. The 55 clips connect the free ends of the parallel sides of the plates and the other sides 4 of the plates or bars 1 project in opposite directions to each other, as seen most clearly in Figures 4, 5 and 6.

It will be seen that I provide two semi-circular tracks spaced apart and connected at their upper free ends by truss rods such as 5. In each case the tracks are supported by base members in the form of blocks 6 secured to the floor 7 by any suitable securing devices such as 8. The blocks are formed with recesses 9 receiving the tracks and are rigidly connected to the tracks, as indicated at 10. The intermediate portion 65 of the tracks rests upon or is located below the surface of the ground or floor and the ends of the track are presented upwardly, as seen most clearly in Figures 2 and 3.

11, 11 represent a pair of semi-circular or 75 arcuate racks. One of the racks is mounted in each of the tracks. These racks include flanges 12 riding upon the upper sides 4 of the plates or rails 1 and central depending ribs 13 accommodated between the plates 80 and formed with toothed lower edges 14. Clips 15 bolted to the outwardly projecting edges of the flanges 12 at intervals throughout the length of the racks are engageable under the flanges of the plates 1 to insure 85 a smooth sliding movement of the racks within the tracks. The supporting blocks 16 carried by the racks 11 provide points of attachment for the opposite ends of a pair of longitudinal rails 17, upon which an 90 automobile such as 18 may be supported. A car may be introduced onto the rails by running the same up a drawboard 19 at one end of the supporting frame, or in any other 95 convenient manner.

I have shown one convenient means of firmly securing the car to the rails 17 for the purpose of firmly holding the car during the turning operation. This securing means includes U-bolts 20, the intermediate portions of which bear against a felly 21 of a wheel of the machine and the ends of which straddle the rails 17. The screw threaded ends of the U-bolts receive cross heads 22 and nuts 23 screwed onto the threaded ends 105 of the bolts clamp the cross heads 22 against the under faces of the rails to securely hold the wheels of the automobile against the

rails. Cushioning pads such as 24 are interposed between the intermediate portion of the bolts 20 and the felly 21 of the wheel so that the paint work on the felly will not be marred.

From the foregoing description it will be seen that in order to turn the car on its side or swing the same about, it will merely be necessary to provide some means for sliding the racks 11 within the tracks 1, and I have shown one practical operating means for this purpose. A shaft 25 is journaled between two of the bearing blocks 6 and pinions 26 keyed to the shaft are engageable with the teeth of the racks 11 to operate the same. At one end of the shaft 25, a ratchet clutch member 27 is keyed to the shaft. A crank handle 28 mounted to rotate on the end of the shaft includes a ratchet face 29 which is normally held in engagement with the ratchet clutch member 27 by an expansion spring 30 around the shaft 25 acting on the crank handle.

Adjacent the crank handle, a U-shaped bracket 31 is fixed to each of the tracks. Within these brackets double-ended pawls 32 are pivotally mounted upon pins 33. A stud 34 is provided at the intermediate portion of each bracket 31. Contraction springs 35 may be selectively stretched between the stud 34 and either one of a pair of extensions or lugs 36 at opposite sides of the pivot pin 33 and integral with the pawl, thereby selectively holding either end of the pawl in engagement with the teeth of the rack with which said pawl is associated.

The operation of the device is as follows: After a car has been locked in position upon the rails 17, the crank handle 28 is turned back and forth. Movement of this crank handle in one direction causes the pinions 26 to turn the racks 11 within the tracks. Movement of the handle in the other direction has no effect because of the ratchet clutch member above described. The pawls 32 are in the position shown in Figure 7, preventing accidental retrograde movement of the racks within the tracks. Continued turning of the crank handle will move the tracks and the car which is carried by the tracks to the position shown most clearly in Figure 3, where it may be conveniently worked upon. When it becomes desirable to restore the car to its normal position, the springs 35 associated with the pawls 32 are reversed so that the other ends of the pawls come into place. The crank handle 28 may then be grasped and pulled out of engagement with the clutch member 27. The weight of the car will automatically restore the racks to their normal position and the pawls 32 will prevent undue oscillation or rocking of the car as it returns by gravity to the position shown in Figure 2.

Although I have illustrated certain of the

preferred embodiments of my invention, it will be evident that various slight changes and alterations might be made in the general form and arrangement of the parts described without departing from the invention, and hence I do not wish to limit myself to the precise details set forth, but shall consider myself at liberty to make such slight changes and alterations as fairly fall within the spirit and scope of the appended claims.

I claim:

1. In a device of the character described, a pair of arcuate tracks, arcuate racks slideable in the tracks, means associated with the racks for supporting a car and means for sliding the racks in the tracks.

2. In a device of the character described, a pair of arcuate tracks, arcuate racks slideable in the tracks, means associated with the racks for supporting a car, means for sliding the racks in the tracks, said last-mentioned means including pinions engageable with the racks, and means for turning the pinions.

3. In a device of the character described, a pair of arcuate tracks spaced apart and connected, arcuate racks mounted to slide in the tracks, rails connecting and carried by the racks, said rails being adapted to support an automobile, and means for sliding the racks to turn an automobile supported on the rails.

4. In a device of the character described, a pair of arcuate tracks spaced apart and connected, arcuate racks mounted to slide in the tracks, rails connecting and carried by the racks, said rails being adapted to support an automobile, means for sliding the racks to turn an automobile supported on the rails, and means for locking the racks in any desired position.

5. In a device of the character described, a pair of arcuate tracks spaced apart and connected, arcuate racks mounted to slide in the tracks, rails connecting and carried by the racks, said rails being adapted to support an automobile, means for sliding the racks to turn an automobile supported on the rails, means for locking the racks in any desired position, and said last mentioned means including pawls engageable with the racks.

6. In a device of the character described, a pair of arcuate tracks spaced apart and connected, arcuate racks mounted to slide in the tracks, rails connecting and carried by the racks, said rails being adapted to support an automobile, means for sliding the racks to turn an automobile supported on the rails, means for locking the racks in any desired position, said last-mentioned means including pawls engageable with the racks, and said pawls arranged to check the movement of the racks in either direction.

7. In a device of the class described, pairs of arcuate angle plates spaced apart and rigidly connected to form tracks, racks slid-

able in the tracks, rails connecting the racks, and pinions engageable with the racks to slide the same.

8. In a device of the class described, pairs of arcuate angle plates spaced apart and rigidly connected to form tracks, racks slideable in the tracks, rails connecting the racks, pinions engageable with the racks to slide the same, and means engageable with the 10 racks to hold them against accidental movement in either direction.

9. In a device of the class described, pairs of arcuate angle plates spaced apart and rigidly connected to form tracks, racks slideable in the tracks, rails connecting the racks, pinions engageable with the racks to slide the same, and means for manually operating 15 the pinions.

10. In a device of the class described, 20 pairs of arcuate angle plates spaced apart and rigidly connected to form tracks, racks slideable in the tracks, rails connecting the racks, pinions engageable with the racks to slide the same, means for manually operating 25 the pinions, said means including a common shaft whereon said pinions are mounted, a spring pressed crank handle on

the shaft, and a ratchet clutch associated with said handle.

11. In a device of the character described, 30 a pair of arcuate tracks, each of said tracks comprising a pair of arcuate angle irons secured together in spaced relation, a carriage movable on the tracks, said carriage being provided with arcuate racks to engage 35 the space between the angles of the tracks, supports for the tracks, pinions carried thereby and positioned within the space between the track angles to engage the racks of the carriage and means to rotate the 40 pinions to move the carriage on the tracks.

12. In a device of the character described, 45 a pair of arcuate tracks, means to support the same in vertical planes and in spaced relation having their centers in horizontal alinement, a carriage movable on the tracks, arcuate racks carried by the carriage and engaging the tracks, a pinion carried by the supports and engaging the racks and a crank carried by the pinion whereby the same may 50 be rotated to swing the carriage about the axis of the arcuate tracks.

WILLIAM P. KRAMER.
